Claims priority, application Germany Sept. 20, 1955

4 Claims. (Cl. 292—198)

This invention relates to a safety latch device particularly adapted for use on vehicle bodies to prevent door separation from the body pillar in a fore-and-aft direction.

The conventional latch bolt coating with a striker or keeper device is intended only to hold a vehicle door in closed or latched condition against swinging movement about the door hinges. However, such devices frequently fail to keep the vehicle door securely latched under abnormal conditions, such as when the vehicle is involved in a collision or is upset. The modern vehicle body is only a relatively rigid structure. Collision or upset impacts often cause body deformation and relative movement between the vehicle parts and more particularly between the doors and door framing members. Such body deformation and relative movement between the vehicle door and framing member or body pillar often causes the latch bolt to be pulled away from the striker or keeper in a direction longitudinally of the vehicle body permitting the vehicle door to fly open and the vehicle occupants to be thrown from the vehicle even though the latch mechanism itself may actually remain in latched condition.

It is an object of the present invention to provide a simple and inexpensive improvement in a cooperating latch bolt and keeper device which will effectively inhibit lateral movement, that is, movement in a direction longitudinally of a vehicle body, to a degree sufficient to prevent the latch bolt and keeper device from becoming laterally disengaged. It will be understood that some degree of lateral movement must be permitted to occur since certain tolerances and clearances must be permitted in the fitting together of the vehicle body components to compensate for manufacturing inaccuracies. The present invention permits normal manufacturing tolerances and clearances to be maintained while at the same time making provision for limiting the permissible lateral movement of the bolt and keeper device relative to one another so that the two cannot become abnormally disengaged.

Further objects and advantages and the features of construction embodied in the present invention to attain the same will be apparent from the following description and appended claims, reference being had to the accompanying drawing forming a part of this specification wherein like reference numerals designate corresponding parts in the several views.

Fig. 1 illustrates the front face of a latch mechanism and shows a latch bolt mounted thereon constructed in accordance with the present invention, the latch bolt being shown in relation to a keeper device. Fig. 1 is a section looking in the direction of the arrows 1—1 of Fig. 2.

Fig. 2 is a view looking in the direction of the arrows 2—2 of Fig. 1.

Fig. 3 is a view illustrating the latch bolt of the present embodiment in several operative positions.

2

Before explaining in detail the present invention, it is to be understood that the invention is not limited in its application to the details of construction and arrangement of parts illustrated in the accompanying drawing, since the invention is capable of other embodiments and of being practiced or carried out in various ways. Also, it is to be understood that the phraseology or terminology employed herein is for the purpose of description and not of limitation.

10 In the drawing there is illustrated, by way of example, a particular embodiment of the present invention as applied to the doors and frame structures of an automobile body. The embodiment of the invention as illustrated in Figs. 1 to 3 comprises a latch bolt device 49 and a

15 striker or keeper device, generally designated 34.

The latch bolt device 49 comprises a lever or finger-like latch element 50 having a substantially figure eight contour. The latch element 50 is pivotally mounted on the latch plate 13, the pivot axis being substantially at the center of the lower portion 51 of the element. The latch element 50 extends in a generally upwardly direction and is swingable in a plane parallel to the front face of the latch plate 13. The latch element 50 is connected by means of its pivot stud 15 to a ratchet (not shown) 20 adapted to be engaged by a spring urged pawl (not shown) which may be disengaged from the ratchet by an outer manually operable lever means or an inner manually operable lever means (not shown). The inner mechanism of the latch mechanism forms no part of the present invention and the foregoing brief description is deemed sufficient to establish a background for understanding the present invention.

When the vehicle door is open the latch element 50 by 25 action of the latch mechanism spring urged pawl acting against the ratchet will be maintained in the solid outline position shown in Fig. 3. In this position the latch element 50 is pointing obliquely upwards toward the interior of the vehicle door. As the door is swung to a closed

30 position the latch element 50 engages the striker or keeper 34 and is turned upwards. Should the door not be completely closed, the latch element 50 will assume the intermediate dot and dash outline position shown in Fig. 3 or the safety locking position. Although the vehicle door

35 is not completely latched, it will be prevented from swinging in an open direction, as will be explained. When the door is completely latched the latch element 50 assumes the solid outline position shown in Fig. 1. In both the intermediate dot and dash outline position and the solid line position of Fig. 1, the latch element 50 is held against 40 swinging movement in an unlatching direction by coaction of the pawl and ratchet. The latch element 50 may be returned to its open or solid outline position shown in Fig. 3 only upon disengagement of the pawl from the ratchet by actuation of the outer or inner manually operable release means.

45 The striker or keeper device 34 has a body or frame member 35 substantially in the form of the letter C, the opening being toward the outside of the vehicle. The frame member 35 may be made of any suitable material, such as a plastic or die cast metal. The frame member 50 comprises a bottom or foot portion 36, an ascendant or erect rib 37 and a head portion 38 of essentially hook form.

55 A steel plate 39 provides a safety interlock feature. The steel plate 39 is of substantially C shape having a smaller opening 40 than the frame member opening. Whereas, the foot portion 36 of the frame member 35 is provided with a depressed surface 41, the plate 39 foot portion 42 is provided with a substantially flat upper surface 43 which is at a somewhat higher level than the surface 41. It will be noted that the head portion 44 of

60 65 70

the plate 39 is not of a hook form and that the lower surface 45 thereof extends somewhat below the lower surface of the frame member head or hook portion 38.

The plate 39 is secured to the frame member 35 by rivets 46. Both the frame member 35 and the plate 39 are provided with aligned holes adapted to receive bolts 47 for securing the striker or keeper 34 to the vehicle body pillar 48.

It may be noted here that the striker or keeper device body portion may be made of plastic material of high strength, e.g., of plastic of the polyurethane groups. However, it would be feasible to make the striker or keeper body of steel in which case the plate portion 39 might be formed integrally therewith.

The latch bolt device 49 comprises a lever or finger-like latch element 50 having a substantially figure eight contour, as described above. The lower portion of the latch element 50 is provided with a flange 52 extending below the roller 25 journaled on the shaft 15, for a purpose to be explained.

Substantially at the center of the upper half portion 53 of the latch element 50 there is provided a stop or button 54 preferably made of some plastic material of high resistance, such as a plastic of the polyamide or polyurethane groups. The shank 55 of the button 54 may be press fit or riveted in a suitable aperture in the latch element 50.

In operation the present embodiment operates as follows: As the vehicle door is moved from an open to a closed position, the latch element 49 abuts the erect rib 37 of the striker or keeper frame member 35. The latch element is turned upwardly from its oblique position shown in solid outline in Fig. 3 through the intermediate dot and dash outline position or the safety latch position to its final vertical dot and dash outline position. This last position represents the final latched position of the bolt.

In both the safety and the final latched positions the upper end of the upper half portion 53 of the latch element 50 is opposed by the corner 56 of the frame member head portion 38. In the safety latched position the door is loosely held but cannot be opened. In the final latched position, the upper end of the latch element 50 is substantially encompassed by the head portion 38. The lower portion of the latch element is, as shown, supported by the roller 25 riding on the upper surface 43 of the plate 39 foot portion 42.

Lateral disengagement of the latch bolt 49 from the striker or keeper device 34 is effectively prevented by the plate 39. Except for the slight movement that might be permitted to occur because of the clearance between the stop button and the inner surface of the plate 39 head portion, the relationship of the latch device 49 and the plate 39 will resist any force tending to cause the latch device to be laterally disengaged from the striker or keeper 34. Should the button 54 be crushed or should the latch element 50 twist under impact, the flange 52 at the lower end thereof would abut the inner surface of the foot portion 42 of the plate 39. Thus, the latch element 50 is effectively opposed against lateral disengagement at both its top and bottom.

I claim:

1. In combination, a latch device mounted on the vertical free edge wall of a swinging door, said latch device comprising a latch element having a substantially figure eight contour, pivot means supporting said latch element for swinging movement from a door unlatched position to a door latched position, the pivot axis being substantially at the center of the lower portion of said latch element, roller means carried by said pivot means, and a keeper device mounted on a vertical face of a body pillar to which said free edge wall is latchable, said keeper device comprising a generally C-shaped frame member having a foot portion, a head portion and a rib portion connecting said foot and head portions, a generally C-shaped

plate member secured to said frame member on the side thereof toward the free edge wall of the door, said plate member having a first part thereof projecting above said frame member foot portion and a second part thereof projecting below said head portion, said first part supporting said latch device through said roller means when said frame member head portion engages the free end of said latch element to retain the swinging door in latched position, said second part being effective to prevent disengagement of the latch device from the keeper device in a direction laterally of the direction in which the latch device is moved for normal engagement and disengagement with the keeper device.

2. In combination, a latch device mounted on the vertical free edge wall of a swinging door, said latch device comprising a latch element having a substantially figure eight contour, pivot means supporting said latch element for swinging movement from a door unlatched position to a door latched position, the pivot axis being substantially at the center of the lower portion of said latch element, roller means carried by said pivot means, said lower portion having a flange extending below the periphery of said roller means, and a keeper device mounted on a vertical face of a body pillar to which said free edge wall is latchable, said keeper device comprising a generally C-shaped frame member having a foot portion, a head portion and a rib portion connecting said foot and head portions, a generally C-shaped plate member secured to said frame member on the side thereof toward the free edge wall of the door, said plate member having a first part thereof projecting above said frame member foot portion and a second part thereof projecting below said head portion, said first part supporting said latch device through said roller means when said frame member head portion engages the free end of said latch element to retain the swinging door in latched position, said first and second parts being effective to prevent disengagement of the latch device from the keeper device in a direction laterally of the direction in which the latch device is moved for normal engagement and disengagement with the keeper device.

3. In combination, a latch device mounted on the vertical free edge wall of a swinging door, said latch device comprising a latch element having a substantially figure eight contour, pivot means supporting said latch element for swinging movement from a door unlatched to a door latched position, the pivot axis being substantially at the center of the lower portion of said latch element, roller means carried by said pivot means, and a keeper device mounted on a vertical face of a body pillar to which said free edge wall is latchable, said keeper device comprising a generally C-shaped frame member having a foot portion, a head portion and a rib portion connecting said foot and head portions, said keeper device having a first part thereof projecting above said frame member foot portion and a second part thereof projecting below said head portion, said first part supporting said latch device through said roller means when said frame member head portion engages the free end of said latch device to retain the swinging door in latched position, said second part being effective to prevent disengagement of the latch device from the keeper device in a direction laterally of the direction in which the latch device is moved for normal engagement and disengagement with the keeper device.

4. In combination, a latch device mounted on the vertical free edge wall of a swinging door, said latch device comprising a latch element having a substantially figure eight contour, pivot means supporting said latch element for swinging movement from a door unlatched to a door latched position, the pivot axis being substantially at the center of the lower portion of said latch element, roller means carried by said pivot means, and a keeper device mounted on a vertical face of a body pillar to which said free edge wall is latchable, said

keeper device comprising a generally C-shaped frame member having a foot portion, a head portion and a rib portion connecting said foot and head portions, said keeper device having a first part thereof projecting above said frame member foot portion and a second part thereof projecting below said head portion, said first part supporting said latch device through said roller means when said frame member head portion engages the free end of said latch device to retain the swinging door in latched position, said first and second parts being effective to prevent disengagement of the latch device from the keeper device in a direction laterally of the direction in which the latch device is moved for normal engagement and disengagement with the keeper device.
